GARMENT

William A. Boetcker, Flushing, N. Y., assignor to
Talon, Inc., a corporation of Pennsylvania

Application September 27, 1938, Serial No. 231,890

5 Claims. (Cl. 2—234)

This invention relates to garments and particularly to an improved fly construction for trousers. The invention is an improvement upon the trouser construction shown in the Craig Patent 1,960,218, granted May 22, 1934.

While the construction of the Craig patent has been used commercially it has been found especially in trousers made of light weight material, that the fastener will make an impression in the front face of the fly in the severe pressing operations employed by tailors. Various attempts have been made to solve this problem but up to the present time none of them have been successful.

The principal object of my invention therefore is to solve the problem above explained and to produce a construction which will stand severe pressing operations without showing an impression or embossing of the fastener through the cloth.

A further feature of my invention is to eliminate the forcing out of the fastener chain at the top of the fastener by the slider when in closed position.

Other objects of my invention will hereinafter more fully appear. In the accompanying drawing I have shown for purposes of illustration one embodiment which my invention may assume in practice. In the drawing:

Fig. 1 is a front view of a pair of trousers with a slide fastener closing;

Fig. 2 is a cross-section showing the relative arrangement of the various parts schematically and showing how they are stitched together;

Fig. 3 is a cross-section on line 3—3 of Fig. 1;

Fig. 4 is a perspective view of the padding strips;

Fig. 5 is an inner face view of the left fly; and

Fig. 6 is a detail view of the upper end of the fastener when closed.

Referring to the drawing the trousers include a right body portion 7 and a left body portion 8 with a front fly opening generally designated 9. The fly consists of a pair of overlapping flaps the inner or right flap being designated 10 and the outer or left one 11. Any convenient attachment may be employed at the belt line such as the button 12 and hook 13. A slide fastener disposed between the flaps is provided for closing the opening and it comprises a pair of tapes 14, 15 having rows of fastener elements 16 attached to their adjacent edges. A slider 17 slides over the rows of fastener elements for engaging and disengaging them in a well known manner. The tape 15 is secured to the left or front flap 11 and the tape 14 is secured to the right flap 10.

In the construction of the inner or right fly the front of the garment 7 extends to a point closely adjacent the fastener elements and terminates in a hemmed edge 18. The right fly or flap underlies the fastener and is secured to the 5 hemmed edge 18 by suitable rows of stitching 20 which also pass through the fastener tape 14. An inner lining or facing 21 is provided back of the flap 19. It also has hemmed edges 22 and 23. In the construction of the front or left flap the 10 front body portion 8 extends across the fastener and terminates in a hemmed edge 24. The left fly is positioned back of this edge and it has a hemmed outer edge 26.

Although in many cases a single padding strip 15 of suitable thickness and of suitable material may be employed, preferably a pair of canton flannel padding strips 27, 28 are positioned between the strip 25 and the front flap, the strip 27 being somewhat wider than the strip 28. The outer 20 edges of these strips overlie the inner fastener tape 15 and extend to a position closely adjacent the fastener elements 16 but do not overlie them. The edges of the strips adjacent the fastener elements are in alignment while the opposite edges 25 are not. This provides a maximum thickness adjacent the fastener elements and at the same time, avoids any thick shoulder along the opposite side of the padding. It will be observed that due to the hemmed edges of both sides of the 30 cloth and lining strips, the material on the right side (left side as viewed in the drawing) alongside the fastener elements is thicker than it would normally be on the opposite side. In the absence of the padding strips 27, 28 there is a 35 sharp shoulder or ridge caused by the fastener elements. Any severe pressing operations therefore would make an impression through or embossing on the cloth. The padding strips are of such thickness as to compensate for the extra 40 thickness of the fastener elements on that side, it being observed that no such extra compensation is needed on the opposite side because of the extra thickness. In this manner the heavy pressure operations will be distributed throughout 45 a wide area and will not cause the fastener element to make an impression on the front surface of the cloth. Preferably the padding strips extend substantially throughout the length of the fastener and are curved at their lower ends 50 as shown in Fig. 4 at 29.

Another advantage of this construction is that the front of the fly will lie smoother and flat as will be seen from the drawing.

As seen at the upper portion of Fig. 5 and in 55

Fig. 6, the upper end of the left fastener stringer is curved inwardly at 30. This curvature extends for approximately the length of the slider 17 and is for the purpose of accommodating the slider in its position at the upper end without pushing the outer stringer toward the edge of the fly opening. This provides a neater and more satisfactory construction.

While I have shown and described in this application one embodiment which my invention may assume in practice, it will be understood that this embodiment is merely for the purpose of illustration and that various other forms may be devised within the scope of my invention as set forth in the appended claims.

What I claim as my invention is:

1. In trousers having a fly opening, the combination of a pair of overlapping flaps, a slide fastener disposed between the flaps for closing

20 the opening, the slide fastener including a pair of tapes and a row of fastener elements on each tape of greater thickness than the tapes, one of the tapes being secured to each flap, and a strip of padding in one of said flaps extending along-
25 side and closely adjacent the fastener elements to offset to a substantial degree the thickness of the fastener elements.

2. In trousers having a fly opening, the combination of a pair of overlapping flaps, a slide fastener disposed between the flaps for closing
30 the opening, the slide fastener including a pair of tapes and a row of fastener elements on each tape of greater thickness than the tapes, one of the tapes being secured to each flap, and a strip of padding in one of said flaps extending along-
35 side the inner row of said fastener elements and closely adjacent thereto to offset to a substantial degree the extra thickness of the fastener elements.

40 3. In trousers having a fly opening, the combination of a pair of overlapping flaps or flies, a slide fastener disposed between the flaps for closing the opening, the slide fastener including

a pair of tapes and a row of interlocking elements on each tape of greater thickness than the tapes, one of the tapes being secured to each flap, and a strip of padding in the front flap or fly positioned to overlie a substantial portion of the inner tape but not to extend over the fastener elements to offset the extra thickness of the fastener elements.

4. In trousers having a fly opening, the combination of a pair of overlapping flaps, a slide fastener disposed between the flaps for closing the opening, the slide fastener including a pair of tapes and a row of fastener elements on each tape of greater thickness than the tapes, one of the tapes being secured to each flap, the inner or right fly being secured to the right front closely adjacent the right or outer row of fastener elements, and hemmed edges on the right front, left front and linings providing an extra thickness of material along the outer side of the rows of fastener elements which substantially offsets the extra thickness of the fastener elements, and a strip of padding in one of said flaps extending alongside and closely adjacent the fastener elements to offset to a substantial degree the extra thickness of the fastener elements on the other side.

5. In trousers having a fly opening, the combination of a pair of overlapping flaps, a slide fastener disposed between the flaps for closing the opening, the slide fastener including a pair of tapes and a row of fastener elements on each tape of greater thickness than the tapes, one of the tapes being secured to each flap, a front or left fly, the left front of the trousers extending across the left fly, and a padding strip disposed between said left fly and extension in position to overlie the fastener tape and extending to a position adjacent to but not overlying the fastener elements, said padding strip being of a thickness to offset to a substantial degree the extra thickness of the fastener elements.

WILLIAM A. BOETCKER.
